[57] CLAIM

I claim the ornamental design for a golf bag and club protective cover, as shown and described.

DESCRIPTION

FIG. 1 is a perspective view of the golf bag and club protective cover showing my new design;

FIG. 2 is a front elevational view thereof;

FIG. 3 is a side elevational view, with the opposite side elevational view being a mirror image thereof;

FIG. 4 is a rear elevational view thereof;

FIG. 5 is a top plan view thereof;

FIG. 6 is a bottom plan view thereof;

FIG. 7 is a perspective view, with the hood shown in an open position;

FIG. 8 is a front elevational view thereof;

FIG. 9 is a side elevational view, with the opposite side elevational view being a mirror image thereof;

FIG. 10 is a rear elevational view thereof;

FIG. 11 is a top plan view thereof; and,

FIG. 12 is a bottom plan view thereof.
